JOSEPH RITTER, OF ORIZABA, MEXICO.

HYDRAULIC PUMP.

1,197,401.

Specification of Letters Patent. Patented Sept. 5, 1916.

Application filed February 12, 1916. Serial No. 77,913.

To all whom it may concern:

Be it known that I, JOSEPH RITTER, a subject of the King of Italy, and a resident of Orizaba, in the State of Vera Cruz, Mexico, 5 have invented a new and Improved Hydraulic Pump, of which the following is a full, clear, and exact description.

My invention relates to means for automatically raising water by hydrostatic columns to a height greater or equal to the hydrostatic column used for raising the water.

An object of the invention is to provide a simple, inexpensive and efficient valveless 15 hydraulic pump without any reciprocating parts.

Another object of the invention is to provide an hydrostatic pump wherein the liquid raised and the raising liquid may come from 20 independent sources.

With the above and other objects in view, the nature of which will more fully appear as the description proceeds, the invention consists in the novel construction, combination and arrangement of parts as herein 25 fully described, illustrated and claimed.

In the accompanying drawings, forming 30 part of the application, similar characters of reference indicate corresponding parts in both views.

Figure 1 is an elevation of my apparatus, partly in section to show the details of construction, the figure illustrating the apparatus while raising water; and Fig. 2 is a 35 similar view illustrating the apparatus while accumulating water to be raised.

Referring to the drawings, 3 is the distributing tank connected by a conduit 4 to a suitable source of water. An hermetically 40 closed tank 5, positioned at a lower level than the distributing tank 3, is connected therewith by a conduit or pipe 6, the diameter of which is larger than that of the conduit 4. The pipe 6 extends from substantially 45 the top of the distributing tank 3 to substantially the bottom of tank 5, which is the compressor tank. From substantially the bottom of the compressor tank 5 rises a siphon 7, the bend 8 of the siphon being at 50 a slightly lower level than the mouth of the pipe 6 within the distributing tank 3, said siphon 7 discharging into the atmosphere.

An hermetically closed tank 9 is connected to the discharge tank 3 by a U-shaped tube 55 10 extending from the bottom of the distributing tank to the top of tank 9, which

is the charge-receiving tank. The said tank 9 is placed a little lower than the level reached by the water in the distributing tank 3, so that the water flows from the one 60 into the other by gravity. The charge-receiving tank 9 is connected to the compressor tank 5 by a conduit 11 extending through the tops of the tanks 5 and 9. Through this conduit the compression exerted in tank 5 is transmitted to tank 9. The discharge conduit 12 leads from the bottom of the charge-receiving tank 9 to the top of an open tank 13, which is a receiving tank 65 and which is located at any desired height 70 above the tank 9. The discharge pipe is preferably in the shape of a spiral. The capacity of tank 9 is less than the liquid holding of a section of the spiral 12, which section is shorter along the vertical than the 75 shorter branch of siphon 7, that is, shorter than C—H. The capacity of tank 5 must more than exceed the capacity of tank 9 as many times as the height of tank 13, measuring from the tank 9, exceeds the height 80 C—H. For example, if C—H is equal to three feet and tank 13 is thirty feet above tank 9, the capacity of tank 5 must be ten times the capacity of tank 9 plus an excess. 85

The operation is as follows: Water enters 90 constantly into the distributing tank 3 through pipe 4, descends through pipe 10 and fills tank 9 up to the upper end of pipe 11, the pipe 11 being slidably mounted in the tops of the tanks 5 and 9. By moving the end of pipe 11 more or less into tank 9 the receiving capacity of same can be modified. When the water in tank 3 reaches the brim of tube 6 it overflows into tank 5, 95 where it compresses the air and rises gradually into siphon 7. The compression is transmitted through pipe 11 to tank 9. The flow of water through pipe 10 is thus held back, and the contents of tank 9 are forced into the spiral 12. As the water keeps rising in the pipe 6 and siphon 7 all the liquid of tank 9 will soon be inclosed in a given section of the spiral 12 shorter than C—H 100 on the siphon; and as the liquid column so formed is statically lighter than the column of water necessary to reach the overflowing point H in the siphon it gives way constantly before the pressure exerted in tank 5 and is rapidly pushed out and discharged rapidly into tank 13. The same pressure is 105 constantly exerted through pipe 10 as well, but will never repel the water farther than 110

the bend therein for the height from the bend to tank 3 is greater than C—H.

When all the water from tank 9 has been exhausted through the end of spiral 12 the liquid in tank 5 should have risen nearly to come in touch with the lower end of pipe 11. It may be here remarked that by adjusting the lower end of pipe 11 the capacity of tank 5 can be modified as required to work the apparatus with the smallest possible waste of water. It will be seen that as soon as the water comes in touch with pipe 11 within the tank 5 the liquid rises simultaneously in pipes 6 and 11 and in siphon 7, but the shorter arm of the siphon 7 being the shorter of the three, the liquid passes the point H in the siphon and starts the siphon, and the contents of tank 5 are discharged through the longer arm of the siphon. In this phase of the operation the tank 5 acts as an open tank, admitting air through pipe 6. For this purpose pipe 6 is made larger than would be required to carry down the water entering tank 3 through pipe 4. The longer arm of the siphon exceeds the shorter by A—B, and it is materially greater than A—C, the height of water in the tank 5. Due to the fact that a certain suction is exerted and the air is drawn into tank 5 through the conduit 6 which keeps up the flow of liquid through the siphon, and the flow is all the more rapid the greater the length A—B as compared with A—C. In this phase the tank 5 is fed constantly by the small quantity of water delivered by pipe 4 and drained rapidly at given intervals by the large siphon 7.

While tank 5 is being emptied, the pressure keeping back the liquid in pipe 10 is released and water from tank 3 can enter tank 9 (see Fig. 2). In due time siphon 7 runs dry. Water again fills tank 5, whence pressure is again transmitted to tank 9 and the pumping cycle is repeated. Tank 9 can be fed from a different source than tank 3, thus permitting the raising of water or liquid of a different character to any height by means of any kind of water, and this even if the two sources are located far apart, by giving the required length to the air pipe 11.

It will be noticed that my apparatus is devoid of any movable part. Its function is automatic and depends only on the supply of water. Attention is called to the fact that the conduit 6 forms an overflow from the distributing tank and that the siphon is adapted to discharge the contents of the compressor tank at a rate exceeding the supply of the pipe 4 to the distributing tank whereby air enters into the compressor tank, and the cycle of the apparatus is then repeated.

While I have described the principle of operation, together with the apparatus which I now consider to be the best embodiment

thereof, I desire to have it understood that the apparatus shown is merely illustrative and that such changes may be made as are within the scope of the appended claims.

I claim:

1. In an apparatus of the class described, a distributing tank, a compressor tank adapted to be filled with liquid from the distributing tank under a predetermined hydrostatic head, a siphon from the compressor tank for emptying the same at a rate exceeding the supply to the distributing tank, the hydrostatic head of the shorter arm of said siphon being less than the hydrostatic head under which the compressor tank is filled, a charge-receiving, closed tank positioned above the compressor tank, a conduit for supplying liquid to said tank, the hydrostatic head of said conduit exceeding that of the shorter arm of the siphon, a conduit for transmitting air from the compressor tank to the charge-receiving tank, and a liquid outlet from the charge receiving tank to a height exceeding the hydrostatic head of the shorter arm of the siphon as many times as the volume of the compressor tank exceeds that of the charge-receiving tank. 70 75 80 85 90

2. In an apparatus of the class described, a distributing tank, a compressor tank adapted to be filled with liquid from the distributing tank under a predetermined hydrostatic head, a siphon from the compressor tank for emptying the same at a rate exceeding the supply to the distributing tank, the hydrostatic head of the shorter arm of said siphon being less than that under which the compressor tank is filled, a charge-receiving, closed tank positioned above the compressor tank but below the liquid level of the distributing tank, a U-shaped conduit for supplying liquid to said charge-receiving tank from the distributing tank, the hydrostatic head of the U-shaped conduit exceeding that of the shorter arm of the siphon, a conduit for transmitting air from the compressor tank to the charge-receiving tank, the length of said conduit exceeding the length of the shorter arm of the siphon, and a liquid outlet from the charge-receiving tank to a height exceeding the hydrostatic head of the shorter arm of the siphon as many times as the volume of the compressor tank exceeds that of the charge-receiving tank. 95 100 105 110 115

3. In an apparatus of the class described, a distributing tank, a compressor tank adapted to be filled with liquid from the distributing tank under a predetermined hydrostatic head, a siphon from the compressor tank for emptying the same at a rate exceeding the supply to the distributing tank, the hydrostatic head in the shorter arm of the siphon being less than the hydrostatic head by which the compressor tank is filled, a charge-receiving, closed tank posi- 120 125 130

- tioned above the compressor tank but below the liquid level of the distributing tank, a U-shaped conduit supplying liquid to said charge-receiving tank from the distributing tank, the hydrostatic head of the U-shaped conduit exceeding that of the shorter arm of the siphon, and a spiral-shaped conduit from the charge-receiving tank to a height exceeding the hydrostatic head of the shorter arm of the siphon as many times as the volume of the compression tank exceeds that of the charge-receiving tank, the capacity of the receiving tank being less than the liquid holding of a section of the spiral 15 the vertical length of which is less than the shorter arm of the siphon.
4. In an apparatus of the class described, a distributing tank, means for supplying liquid to said tank, a compressor tank below the distributing tank, an overflow from the delivery tank to the compressor tank whereby the compressor tank may be filled from the distributing tank, a siphon from the compressor tank for emptying the same 20 at a rate exceeding the supply to the distributing tank, the hydrostatic head of the shorter arm of the siphon being less than the hydrostatic head in the overflow, a charge-receiving, closed tank positioned 25 above the compressor tank, a conduit for supplying liquid to said charge-receiving tank, the hydrostatic head of said conduit exceeding that of the shorter arm of the siphon, a conduit for transmitting air from 30 the compressor tank to the charge-receiving tank, the length of said conduit exceeding that of the shorter arm of the siphon, and a liquid outlet from the charge-receiving tank to a height exceeding the hydrostatic head 35 of the shorter arm of the siphon as many times as the volume of the compression tank exceeds that of the charge-receiving tank.
5. In an apparatus of the class described, a compressor tank, means for supplying liquid continuously to the tank under a predetermined hydrostatic head, a siphon to empty the tank at a rate exceeding the supply, whereby air enters the tank with the liquid as the tank is emptied by the siphon, the hydrostatic head of the shorter arm of 40 the siphon being less than the hydrostatic head under which liquid is supplied to the tank, and an air outlet from said tank.
6. In an apparatus of the class described, a liquid charge-receiving tank, means for supplying air intermittently to said tank, and a spiral-shaped conduit from said tank, the capacity of the charge-receiving tank being less than the liquid holding of a section of the spiral, the pressure caused by 45 the hydrostatic head of said spiral section being less than the air pressure supplied to the tank.
7. In an apparatus of the class described, a distributing tank, a compressor tank, an overflow from the distributing tank to the compressor tank, a siphon from the compressor tank for emptying the same at a rate exceeding the supply to the distributing tank, whereby air enters the compressor tank through the overflow with the liquid from the delivery tank, the hydrostatic head of the shorter arm of the siphon being less than the hydrostatic head in the overflow, 50 said compressor tank having an air outlet 55 through which the compressed air is intermittently ejected.

In testimony whereof I have signed my name to this specification in the presence of two subscribing witnesses.

JOSEPH RITTER.
